UNITED STATES PATENT OFFICE.

ELMER M. JONES, OF ATLANTA, GEORGIA, ASSIGNOR TO JONES SIGNAL SYSTEM COMPANY, OF ATLANTA, GEORGIA, A CORPORATION OF GEORGIA.

AUTOMATIC TRAIN-STOP.

1,142,884.

Specification of Letters Patent. Patented June 15, 1915.

Application filed October 2, 1911. Serial No. 652,260.

To all whom it may concern:

Be it known that I, ELMER M. JONES, a citizen of the United States, residing at Atlanta, in the county of Fulton and State of Georgia, have invented a certain new and useful Improvement in Automatic Train-Stops, of which the following is a full, clear, and exact description, reference being had to the accompanying drawings.

10 This invention relates to mechanism conveniently called an automatic train stop, and comprises vehicle equipment and track equipment adapted to coöperate therewith to automatically give an indication on the 15 moving vehicle, either by stopping it or giving a signal, or both.

A characteristic of the invention is that the application of the danger indication on the vehicle is always initiated whenever 20 the vehicle passes across a stationary portion of the track device, and this initiation is allowed to automatically complete itself into an effective stopping or signaling unless it is counteracted by movable mechanism which is normally in idle position but 25 may be moved into active position by a suitable signal system, or otherwise. It results from the characteristic described that normally the vehicle passes the track devices without the application of the brake or danger indication, while whenever the 30 movable portion of the track device is thrown to active position the vehicle encountering it receives such indication. It 35 further results that if there is anything out of order with the signal system or the movable parts of the track device, the danger indication is given on the vehicle, and it is only when the parts are in perfect working 40 condition and when the indications are for safety that the danger initiation is counteracted before it has become effective.

The peculiar operation above set out is also a characteristic of my prior Patent No. 45 1,129,201 issued February 23, 1915, which should be referred to for claims dominating the present invention. In the structure shown in that patent the stationary initiating ramp and the counteracting movable 50 ramp of the track device are side by side and act on applying and resetting levers side by side on a locomotive or other vehicle. I have found such an arrangement satisfac-

tory in practice, but, under certain circumstances, it is desirable, in reducing the 55 amount of side clearance required for the locomotive to arrange the levers thereon in alinement. The present invention is designed to provide for this by enabling the constant applying and the selective resetting operations to be caused by alined stationary and movable ramps along the track-way coöperating with alined levers carried by the side of the vehicle, as, for example, secured to the truck of the tender. The invention, consisting of the means by which I accomplish this, is hereinafter more fully explained and the essential characteristics are set out in the claims.

In the drawings, Figure 1 is a side elevation of my track equipment and the vehicle equipment mounted on a suitable truck, as, for example, one of the trucks of the tender; Fig. 2 is a plan of the track equipment; Fig. 3 is a side elevation of such equipment with the movable portions in the elevated or safety position, the normal or danger position being indicated by dotted lines; Fig. 4 is an end view of such track equipment; Fig. 5 is a diagram illustrating the effective operating surface provided by the stationary ramp and the movable ramp when in its normal position; Fig. 6 is a similar diagram showing the effective operating surface provided by the stationary ramp and the movable ramp when the latter is in safety position; Fig. 7 is a longitudinal vertical section through the locomotive equipment; Fig. 8 is a plan of such equipment partly broken away and 80 with the casing omitted; Fig. 9 is a front end view of the resetting shoe; Fig. 10 is a vertical cross section through the locomotive equipment illustrating the mounting of the levers and gates; Fig. 11 is an end view 85 of the case containing the locomotive equipment and showing one of the end gates therein.

Referring first to the track equipment shown in Figs. 1 to 6, 1 represents one of 100 the rails and 2 the ties of the trackway. Mounted on the ties is the stationary frame of the track device. This frame, which may be one integral casting, is shown as consisting of a wedge-shaped standard 3 having foot plates 5 and 6 adapted to rest on

adjacent ties and having an extended base portion 7 formed to extend downwardly along the vertical edge of one of the ties and then longitudinally past the next tie 5 and then upwardly into a foot plate 8 on the next following tie. Rising from this last foot plate is a web 9. The upper portion of the standard 3 terminates in a web 10 having an inclined ramp surface.

10 In front of the web 10 are a pair of ears 11, in which is journaled a rock shaft 12. Mounted rigidly on the rock shaft 12 between the ears is a rock arm 13, and joined to the free end of this arm by a knuckle joint 14 is a bar 15, the other end of which lies alongside of the web 9 and is slidable in the space between the web and a bar 18 carried by a pair of pins 16 and 17 projecting from the web. The knuckle joint 14 referred to is preferably made by cutting away portions of the opposite faces to the overlapping members 13 and 15 to bring these members into alignment and providing a pin 14 with an extended head 20 on one side and a suitable washer 21 and a collar pin 22 on the other. The rock arm 12 is preferably of a bell crank form and is rounded concentrically at its heel, as shown at 24, and this portion is adapted 25 to extend beneath the point of the ramp 10 which is correspondingly concaved at 25.

With the construction described it will be seen that the top surface of the stationary web 10 and the arm 13 and the bar 15 make 30 a continuous double inclined ramp of varying profile, according to the position of the arm 13 and bar 15. Thus, when these parts are in the position shown in full lines in Fig. 3, a ramp is provided having the upward incline of the member 10, a horizontal portion along the top of the member 13, and a downward incline along the top of the member 15. This is indicated in the diagram of Fig. 6 by the characters 10^a, 13^a 40 and 15^a. This is the safety position, and results, by reason of the distance between the upward and downward incline, as hereinafter described, in the immediate counter-acting by the vehicle mechanism of the danger indication initiated by the incline 10. The dotted position in Fig. 3 shows the normal or danger position of the parts. In that case, there is the same upward ramp formed by the web 10, but the downward ramp, instead of being by the member 15, is now made by the top surface of the member 13, the member 15 being in idle position. This is illustrated in Fig. 5 wherein the upward ramp is 10^b and the downward ramp is 13^b.

50 It will accordingly be seen that the rocking of the shaft 12 controls the action of the device on the locomotive and that the parts which are normally in danger position may be raised to the safety position by rocking 55 this shaft. Any failure of the signal mech-

anism to rock the shaft 12 results in the danger indication being given, and when the raising force (which may be an electric current in a motor) ceases the raised arm 13 and bar 15 drop by gravity to danger position. The stationary frame is depressed at 7 and the intermediate tie backed off to allow greater clearance for the arm and bar and prevent any clogging by snow, dirt, etc.

70 The locomotive equipment which cooperates with the ramps described may conveniently be carried in a case on the truck of the locomotive tender. It is so shown in Fig. 1 where the outer wall of the case is designated 30, and the case is shown as mounted 75 on the outer side of the truck 32 of the tender, the case being secured to this truck by suitable angle irons 33 and 34 secured to the end of the case and to the members of the truck. It is to be understood that any 80 suitable means of securing the casing to the truck may be employed.

85 The locomotive equipment is shown in Figs. 7 to 11 inclusive and will now be described. The case which carries the locomotive equipment is shown as consisting of a long, narrow, rectangular box having parallel vertical sides 30 and 31 and vertical ends 38. The box is open below, and on top 90 is designed to be covered by a suitable cover 39 which may extend between the side plates and be held by bolts passing through eyes 37 formed in the under side of the cover plate.

95 The casing is provided with horizontal 100 partitions 40, 41 and 42, making a floor some distance above the lower edge of the casing. Between these partitions and beyond the ends of them are spaces through which project downwardly the different parts which 105 engage the ramps. Thus, near the center of the casing between the partitions 41 and 42 is a main operating lever 45 adapted, as hereinafter explained, to initiate the application of the brake. Beyond this, and 110 adapted to project downwardly through the opening between the partitions 40 and 41 is a resetting shoe 46. At the forward end of the casing, extending downwardly between the partition 42 and the end of the 115 casing is a front gate 47 and at the rear end is a gate 48. These two gates normally depending in front of and behind the operating lever 45 protect it from an unintentional operation by an obstruction along the 120 trackway against which it might strike. The gates extend across openings in the ends 38 of the casing, and as the vehicle passes over the ramp the gates rise and fall 125 as they engage the ramp. I avail myself of this movement of the gates to perform also other operations which will hereinafter be described.

130 The gate 47 has a pair of parallel arms 50 lying alongside of the sides of the casing

and pivoted thereto at 51. Similarly, the gate 48 has a pair of arms 54 having downward ears pivoted to the side members of the casing at 55. The gates are normally held in their lowermost positions by a bar 56 hinged at 58 to one of the arms 54 and a rod 59 hinged at 60 to the corresponding arm 50, the rod 59 extending loosely into a socket 61 in the bar 56, and being surrounded by a compression spring 63 between the head 64 on the rod and the end of the socket. Some loose play is allowed between the end of the rod 59 and the end of the socket. Accordingly, the elevation of either gate is allowed, the spring compressing and tending to return the gate. If either gate, by any jamming, should stick in its elevated position, the raising of the other gate would necessarily force it down, because the clearance would have been taken up between the rod and the base of the socket. Each gate is limited in its downward movement by its arm bearing against the top of the corresponding partitions 40 or 42. In this downward position the gates, extending across the entrance and exit openings on the end walls of the casing effectively protect the main lever 45 against inadvertent operation by any obstruction along the trackway.

70, in Figs. 7 and 8, represents a suitable block carried by one of the side walls of the casing and formed with a chamber and seat to act as the air valve. Within the chamber is a valve plug 71 normally resting on the valve seat above the passageway 72, which is connected with the train air-pipe. Above the valve plug is an exit opening 73. Accordingly, when the valve is raised, the train pipe is vented through the opening 73, and the brakes start to apply.

The valve plug 71 is normally held to its seat by a lever 78, which is pivoted at 79 on a rod carried by the side member and extends through a movable head 80 guided by the chamber. The head rests on a spring 89 which rests on the plug 70. This lever 78 is provided with a pivoted latch 82 pressed by a spring 83 and normally engaging the latch 84 secured to and projecting upwardly from the main lever. This main lever is preferably a plate of the downwardly bent form shown, presenting a nose designed to engage the ramp, the forward end of the plate being secured to a yoke 85, the downward arms of which are pivoted at 86 to the sides of the case. The forward end 87 of the lever is adapted to overlap and rest on the partition 41. Between the lever and a lug on the block 70 is a compression spring 88.

It will be seen that the spring 88 normally holds the lever 45 in its lowermost position, and in this position the latches 84 and 82 hold the bar 78 down, so that the valve plug 71 is maintained on its seat. The stiff

compression spring 89 between the head 80 and valve plug insures the firm seating of the plug, this spring being heavy enough so that the pressure of the air cannot compress it to open the valve.

As the vehicle travels over the ramps in the forward direction; that is from left to right, as shown in the drawings, the gate 47 rises idly and then the lever 45 engages the ramp 10, and, rising into the position shown in dotted lines in Fig. 7, swings the latch 84 to release the latch 82 and thereupon the air pressure in the train pipe raises the valve plug and the train pipe starts to vent. Now, whether this venting becomes effective to apply the brake depends upon whether it is allowed to continue or is immediately counteracted by the restoring of the valve plug, and this depends upon the length of the effective ramp, determined by whether the arm 13 is up or down. This will now be explained.

After the lever 45 has passed over the stationary ramp 10 and has initiated the application of the brake, the gate 48 engages this ramp and is swung upwardly about the pivot 55. Now, this gate is connected by a pair of toggle links 90 and 91 with a lever 93, these links 90 and 91 it is understood have a suitable stop to keep the links always a little above a perfectly straight position. The link 90 is pivoted at 96 to a rod mounted in ears 97 carried by the gate. The lever 93 is pivoted at 94 to an ear or standard 95 secured to and rising from the horizontal plate 40. Hence, as the gate rises, the toggle tends to shove on the offset portion of the free end of the lever 93 pushing it downwardly, and, in such movement, to depress the shoe 46 formed on the free end of the lever. The gate 48 which rests on the partition 41 holds the lever 93 in a horizontal position by means of the tension on the toggle links which pulls them into a position as nearly straight as they can assume. If the ramp is in danger position; that is, with the arm 13 down and the effective ramp of the form shown in Fig. 5, then, when the gate 48 is rising on the ramp 10 (line 10^b, Fig. 5) the shoe 46 is beyond the peak of the ramp, being over the surface 13^b in Fig. 5, and accordingly, the shoe is free to descend and the rising of the gate forces the shoe downward idly. Under these conditions, no resetting of the valve takes place and the initiation of the brake application becomes effective. On the other hand, if the arm 13 be raised so that the effective ramp presents the surface shown in Fig. 6, then, when the gate 48 rises, the resulting downward movement of the shoe 46 is stopped by the shoe striking the horizontal surface of the arm 13 (13^a, Fig. 6); the shoe being stopped, the continued upward movement of the gate 48

buckles the toggle and raises the joint thereof so that this joint engages and presses upwardly on the under side of a resetting lever 100, which is pivoted on the shaft 79 supported by the casing and has its other end overhanging the lever 78. The result is that this resetting lever forces downward the lever 78 and resets the valve before the venting of the train pipe has had time to become effective. It will accordingly be seen that when the arm 13 of the track device is raised there is no application of the brake, while, when it is down, there is an application.

15 It is desirable to provide means for allowing the train to run at very slow speed over the track device when in danger condition. This enables the engineer to flag ahead when the signal system is out of order, or remove obstructions from the track, etc. To accomplish this I provide a governor, which is very simple and at the same time effective. One member of this governor consists of a bar 105 pivoted between ears 106 on lever 45. This bar normally extends approximately horizontal across the top of the lever beyond the front of the valve casing. To the free end of this lever is hinged, at 107, a bar 108. The free end of this bar normally projects into a notch 109 in the shoe 46. Now, with ordinary train speeds, when the lever 45 is lifted, it rises rapidly enough so that it throws the bars 105 and 108 upwardly into the position shown in dotted lines in Fig. 7, whereby the bar 108 is entirely clear of the shoe 46 and that shoe receives its operation by the gate 48 before the bars 105 and 108 have time to fall. In very slow speed of 40 running, however, (for example, five miles an hour or less) before the gate 48 engages the ramp 10, the bars 105 and 106 will have fallen to normal position, as shown in full lines in Fig. 7, and the bar 108, projecting 45 into the notch 109, will restrict the downward movement of the shoe 46. When thus restricted, the continued upward movement of the gate 48 buckles the toggle 90 and 91, and, through the lever 100, resets the valve.

50 The broken line designated *c* in Fig. 7 indicates the horizontal plane across the peak of the ramp. The notch 109, when the bar 108 is active, allows the shoe 46 to descend only to this plane, which is the same position into which it comes when it rests on the horizontal surface of the raised arm 13. This position of the nose of the shoe 46, as well as its lowermost position which it takes when the arm 13 is down, are shown in dotted lines, as are also the corresponding positions of the toggle links.

60 The additional function of the gate 47 heretofore referred to is to reset the valve when it is opened by backward movement of

the vehicle. It will be observed that if the 65 vehicle moves backwardly, that is from right to left, over the ramp, the valve is opened by the lever 45 engaging the bar 15 or the arm 13, according to whether the arm is up or down. In either case, the valve is opened, 70 but before such opening becomes effective, the gate 47 is raised by the bar 15 or the arm 13, and, in such movement, shoves upwardly the under side of the lever 112 pivoted at 113, with the result that the free end 75 of this lever engaging the top of the raised lever 78 (as indicated by dotted lines in Fig. 7) forces that lever downwardly into home position, where it is latched by the latches 82 and 84.

80 To prevent any jamming of the parts just described, the lever 112 has its connection with the gate by means of a downwardly extending nose which rests on a block 115 slidably mounted on a cross bar 116 between the arms of the gate and spring pressed toward the gate to engage the nose on the lever 112 to seat the valve, the further elevation of the gate swinging the plate 115 about the pivot 51 withdraws the plate 90 from beneath the lower end of the lever 112 so that the latter drops by gravity into normal position. On the return stroke of the gate, if the plate 115 bears against the inner side of the lever extension it is forced backwardly against the spring 117 and clears the lever. The spring 117 is light compared to the spring 59. The gate 47 also furnishes 95 convenient means for resetting the valve by hand whenever desired. A simple upward 100 pull on the gate operates through the lever 112 to effect such resetting.

I will now recapitulate the operation of the mechanism of this invention. In normal operation, the vehicle mechanism is in the 105 position shown in full lines in Fig. 7 and the track mechanism is in the position shown in dotted lines in Fig. 3. In this condition, on the forward movement of the train over the ramp, the gate 47 is raised and the 110 lever 112 swung, but both these movements are idle; then, the lever 45 engages the ramp 10 and the air valve is opened, and after the lever passes over the peak of the ramp the 115 lever is returned to normal position by the spring 88. Then, as the gate 48 engages the ramp the lever 93 is swung downwardly, this movement being also idle. Accordingly, the venting of the train pipe continues to a sufficient extent to apply the brake or to give 120 such other indication as may be desired. If, on the other hand, when the train passes over the ramp it is in the safety condition, as shown in full lines in Fig. 3, the gate 47 rises, as before, and is descending along the 125 bar 15 when the lever 45 engages the ramp 10. Accordingly, the lever 112 is in free or idle position and the lever 45 opens the valve.

Now, when the gate 48 engages and rises on the ramp 10, the shoe 46 stands over the horizontal top of the arm 13 and cannot descend below such horizontal plane, and accordingly the toggles 90 and 91 buckle and the toggle joint engaging the resetting lever 100 resets the valve before the venting has applied the brake. If the train speed is below the the prescribed minimum when the locomotive crosses the ramp, the shoe 46 has become locked by the dropping down of the bar 108 before the gate 48 begins to act, and in that case, the toggles are also buckled and the valve reset, allowing the train to proceed. When the brake is applied, it is necessary for the engine man to dismount and reset the valve by raising the gate 47. He can only do this when he is on the ground and the vehicle stopped or running at extremely low speed. It should be noticed that if anything gets out of order or fails to act on either the vehicle equipment or the track equipment, the brake is applied when the stationary ramp is engaged. Accordingly, whenever the engineer passes over a track device and the brake is not applied, he is thereby informed that both the engine equipment and the track device are in proper working order.

Having thus described my invention, what I claim is:—

1. The combination, with a ramp of variable effective length, of means on a vehicle for initiating and counteracting an indication, one of said means being adapted to coact with the ramp irrespective of its length and the other to coact with the ramp or not, according to its length.

2. The combination, of means on a moving vehicle for initiating an indication and means on the vehicle for counteracting such indication, the initiating and counteracting means being located one behind the other with reference to the direction in which the vehicle normally moves, and means along the trackway for controlling the initiating and counteracting means.

3. The combination, with means on a moving vehicle for initiating an indication and means on the vehicle for counteracting such indication, the initiating and counteracting means being located one behind the other with reference to the direction in which the vehicle normally moves, of means along the trackway for actuating the initiating means, and means longitudinally aligned with said last named means with reference to the direction of the movement of the vehicle for controlling the counteracting means.

4. The combination of a track device including stationary and movable ramps and coöperating indication initiating and counteracting devices located one behind the

other on a vehicle, the initiating device being adapted to be controlled by the stationary ramp, and the counteracting device by the movable ramp.

5. The combination of a track device including stationary and movable ramps in longitudinal alinement with each other, and coöperating indication initiating and counteracting devices on a movable vehicle, the initiating device being adapted to be actuated by the stationary ramp, and the counteracting device controlled by the movable ramp.

6. The combination, with means for initiating the application of an indication on a vehicle, of means for counteracting such initiation including a shoe and means for projecting it in the absence of an obstruction when the counteracting means moves, and a movable ramp adapted to restrict or allow such projecting movement according to the position of such ramp to cause or prevent the counteraction of the application.

7. The combination, with a stationary ramp, of means actuated thereby for initiating the application of an indication, and means actuated thereby for counteracting such initiation, the last-mentioned means having a shoe adapted to be projected, and a movable ramp normally out of the path of such projecting movement but adapted to be positioned to engage and stop such shoe.

8. The combination of brake applying and counteracting means on a movable vehicle, a stationary ramp along the trackway adapted to invariably apply the brake on the vehicle when moving along the same in the proper direction, and a ramp alined with reference to the direction of movement of the vehicle with the stationary ramp normally out of position for engagement with the counteracting device but movable into position to cause it to counteract the brake application.

9. The combination of brake applying and counteracting means on a movable vehicle one behind the other with reference to the normal direction of movement of the vehicle, a stationary ramp along the trackway adapted to invariably initiate the application of the brake of the vehicle when moving along the same in the proper direction, and a ramp normally out of position to engage with the counteracting device but movable into position to engage said device causing it to counteract the brake application.

10. The combination of a stationary ramp, mechanism on a moving vehicle adapted to coact therewith to initiate the application of an indication, means behind the initiating means adapted to counteract such application including a member adapted to be pro-

jected, means for projecting it and a movable device in front of the brake applying ramp and movable into and out of position to coact with such projected member to 5 cause the counteraction or permit the application of the indication.

11. The combination, with alined stationary and movable ramps, of indication applying and counteracting levers on a movable vehicle, the stationary ramp operating 10 the applying lever, and the movable ramp controlling the operation of the counteracting lever according to the position of the movable ramp.

12. The combination of an upwardly extending stationary ramp, a depending brake applying lever on a movable vehicle, said lever being adapted to coact with the top of the stationary ramp, depending mechanism 20 thereafter coacting with the top of the stationary ramp including a member movable downwardly, means whereby said mechanism may counteract the brake application provided such member is not permitted to move downwardly, and a movable device in 25 front of the ramp and adapted to stand in position to engage such member or be out of the path thereof.

13. The combination of a stationary ramp, 30 a rock arm adapted to form a continuation of the ramp at different angles according to the position of the arm, mechanism on a movable vehicle adapted to coact with the stationary ramp to initiate the application of a brake, and mechanism on the vehicle for 35 counteracting such initiation, said second named mechanism being controlled by the position of the rock arm.

14. The combination of a stationary ramp, 40 a rock arm adapted to form a continuation of the ramp at different angles according to the position of the arm, means on a movable vehicle for initiating an indication, and mechanism on the vehicle adapted to counteract the initiated indication, said mechanism being controlled by the position of the 45 rock arm but actuated by the engagement of the lever with the stationary ramp.

15. The combination of a stationary ramp, 50 a rock arm, a bar pivoted to the free end of the rock arm suitable guides at the other end of the bar, the ramp, means for positioning the rock arm and bar to make a peak with the stationary ramp or to make a flat 55 surface with two inclines therewith, means on a vehicle adapted to coact with the stationary ramp to apply a brake, and means on the vehicle for counteracting such application, said means having a member projectable toward the ramps and controlling 60 its movement by the position of the rock arm.

16. The combination of a stationary ramp, a rock arm adapted to form a continuation

thereof either downwardly or substantially 65 horizontal, according to the position of the rock arm, brake applying means on a vehicle adapted to coact with the stationary ramp, and counteracting means on a vehicle adapted to be controlled by the position of the rock 70 arm.

17. The combination of a stationary ramp, a rock arm adapted to form a continuation thereof either downwardly or substantially 75 horizontal, according to the position of the rock arm, brake applying means on a vehicle adapted to coact with the stationary ramp, a movable member on the vehicle adapted to engage the ramp, mechanism operated by said member and tending to move into the 80 position occupied by the rock arm when elevated, and means whereby, when the rock arm prevents such movement, the movement of the movable member becomes effective to counteract the brake application. 85

18. The combination, of a track ramp and movable means adapted to stand either as an incline or substantially horizontally, a brake applying mechanism on a movable vehicle, a valve released by said mechanism, a 90 resetting device on the vehicle, a member operating on the ramp, mechanism operated by said member and tending to project itself idly into the position occupied by said movable means when horizontal, and a resetting 95 device for the valve engaged and operated by said mechanism when diverted from its normal movement by the movable means stopping it.

19. The combination of a stationary ramp, 100 a rock arm adapted to form a continuation of the ramp, either as an incline or substantially horizontally, a brake applying lever on a movable vehicle adapted to co-operate with the ramp, a valve released by 105 said lever, a resetting device on the vehicle, a member operating on the stationary ramp, mechanism operated by said member and tending to project itself idly into the position occupied by the arm when horizontal, 110 and a resetting device for the valve engaged and operated by said mechanism when diverted from its normal movement by the rock arm stopping it.

20. The combination of a stationary ramp, 115 a rock arm, a bar joined to the rock arm at its free end, the rock arm being adapted to stand in position to cause it to make a peak with the stationary ramp, means for rocking the arm to make it a substantially horizontal 120 continuation of the ramp with the bar forming a downward incline from such horizontal continuation, initiating mechanism on a moving vehicle adapted to coact with the stationary ramp, and counteracting mechanism on the vehicle adapted to be controlled 125 by the position of the rock arm.

21. The combination, with a track device,

of an air valve on the locomotive, a lever adapted to coöperate with the track device and release the air valve, a lever for resetting the valve, mechanism for operating 5 said latter lever, said mechanism including a movable member adapted to control the resetting of the valve, means on the track device for impeding the movement of said movable member, said mechanism being 10 non-effective to move the resetting lever when said movable member of the mechanism is unimpeded but operative when such member is impeded.

22. The combination, with a track device, 15 of an air valve on the vehicle, a lever for releasing it and mechanism for resetting it, said last mentioned mechanism including an operating part adapted to engage the track device, a shoe adapted to engage the 20 track device, a displaceable connection between the two, the valve resetting mechanism adapted to be engaged by the connection when displaced by the impeding of the shoe.

25 23. The combination, with a track device, of a valve on a vehicle, a lever for releasing the valve, a lever for resetting the valve, operating mechanism for the resetting lever including a lever, a shoe, and a toggle connection 30 between the two adapted when displaced to engage and operate the resetting lever, said track device acting as a movable abutment adapted under one condition to impede the shoe resulting in the displacement of the toggle and under another condition to allow the shoe to move without the displacement of the toggle.

24. The combination, with a track device, 40 of a vehicle equipment including a valve, a lever operated by impinging the track device for releasing it, and a governor operated by the momentum of said lever, a resetting device including a member movable by the track device and mechanism operated 45 thereby adapted to reset the valve or move idly without such resetting, the governor being adapted to act on the last mentioned mechanism and prevent the idle movement.

25. The combination, with a track device, 50 of vehicle mechanism including a valve and a lever adapted to impinge the track device for releasing it, resetting means for the valve, mechanism normally in active position for operating the resetting means, and 55 a latching device adapted to hold said mechanism in active position, said latching device including a member thrown to idle position by the momentum of the operating lever.

60 26. The combination, with a track device, of a vehicle equipment including a valve, a lever adapted to impinge the track device for releasing it, a governing device having a pair of joined links operated by the mo-

mentum of said lever, resetting mechanism 65 including a member movable by the track device, and mechanism operated thereby adapted to reset the valve or move idly without such resetting, the governing device being adapted to prevent the idle movement. 70

27. The combination, with a track device, of a vehicle mechanism including an air valve, a lever adapted to impinge the track device for releasing it, a lever for resetting it, mechanism for actuating the resetting 75 lever including an operating member, a shoe and connecting links, and a governor for latching the shoe in position to cause the links to operate the resetting lever when the member is operated, said governor being thrown to idle position by the momentum of the releasing lever and tending to return by gravity into latching position.

28. The combination, with an air valve, a track device, a lever adapted to impinge the 85 track device for releasing the air valve, mechanism for resetting it, and latching mechanism for holding the resetting mechanism in active position said latching mechanism being thrown by momentum of the 90 releasing lever into idle position and tending to return by gravity to active position.

29. The combination with an air valve, a lever for releasing the same, mechanism for resetting the valve, latching mechanism 95 adapted to engage a portion of the resetting mechanism to render it effective, said latching mechanism being thrown by momentum of the releasing lever into unlatching position and tending to return by gravity to 100 latching position, and a track device having means for operating the releasing lever, and means for moving a portion of the resetting mechanism which movement is rendered effective by the governing mechanism returning to latching position before the said movement occurs.

30. The combination, with a track device, of vehicle equipment having an operating member adapted to engage the track device, 110 pivotally mounted gates for protecting said member against inadvertent operation by obstructions, and a spring connection between said gates whereby either when raised is given a tendency to return. 115

31. The combination, with a track device, of vehicle equipment having an air valve, a releasing lever therefor adapted to engage the track device, pivotally mounted gates for protecting said lever against inadvertent 120 operation by obstructions, and a spring connection between said gates whereby either when raised is given a tendency to return, said connection including a pair of slidably connected links pivoted to the gates, and a 125 spring tending to resist movement of the pivots of such links toward each other, means for limiting such movement, where-

by, when either gate is raised, the raising of the other forces down the first mentioned gate.

32. The combination, with a track device, 5 of a vehicle equipment including an air valve, a lever for releasing it, resetting mechanism for the air valve, a pair of end gates adapted to protect the lever, and mechanism operated by one end gate for 10 resetting the valve on the forward movement, according to the condition of the track

device, and mechanism operated by the other gate for resetting the valve on backward movement independently of track conditions.

15

In testimony whereof, I hereunto affix my signature in the presence of two witnesses.

ELMER M. JONES.
